Gillam D. Godwin,
by Parker Cook, Atty.

UNITED STATES PATENT OFFICE.

GILLAM D. GODWIN, OF WADE, NORTH CAROLINA.

STOP.

1,259,847.

Specification of Letters Patent. Patented Mar. 19, 1918.

Application filed April 14, 1917. Serial No. 161,978.

To all whom it may concern:

Be it known that I, GILLAM D. GODWIN, a citizen of the United States, residing at Wade, in the county of Cumberland and State of North Carolina, have invented certain new and useful Improvements in Stops, of which the following is a specification.

My invention relates to new and useful improvements in stops to be applied to a swinging member wherein it is desired to have the swinging member retained in any set position.

The device is especially applicable to mirrors that are set in bureaus, washstands, dressers, etc., although the device might equally well be applied to a swinging window or transom.

One of the objects of my invention is to provide a stop that is exceedingly simple in structure, that may be quickly and readily applied to the article to which it is to be attached.

Another object of my invention is to provide a stop as herein shown that comprises but practically three parts; that is two attaching members and a spring positioned in one of them.

Still another object of my invention is to provide a stop wherein both members of the stop form a bearing for the article to which the same is attached, or in other words, it is not necessary to provide both a supporting means and positioning means as the members perform both functions.

Still another object of my invention is to provide a stop wherein the spring member may be easily replaced if for any reason it would become worn or lose its resiliency.

With these and other objects in view my invention consists in certain new and useful improvements and combinations of parts as will be hereinafter more fully described and pointed out in the claims.

Referring now to the drawings, Figure 1 is a rear elevation of a swinging mirror showing my improved stop in position.

Fig. 2 is a perspective view of the stop.

Fig. 3 is a side elevation of one of the members of the stop.

Fig. 4 is a side elevation of the other member, and

Fig. 5 is a top plan of the member shown in Fig. 4.

55 In the drawings:

Referring first to Fig. 2 it will be seen

that my improved stop consists of broadly two parts one of which I call the spring retaining member 1, and the other the supporting member 2. The spring member 1 is preferably rectangular in shape and having two cut out portions 3 and 4 at its rear surface. This member 1 is preferably bulged at its outer central portion as at 5, and is provided with an opening 6 for the reception 60 of a pin 7 which is secured to the member 2 and which will be hereinafter referred to.

This member is also provided with two openings 8 and 9 for the reception of screws 10 which fasten the member 1 to the posts 70 or supports for a mirror frame, or to any other member to which the same is to be attached.

In the cut out portions 3 and 4 and surrounding these openings 8 and 9 are the 75 flanged portions 11 and 12 for the reception of the ends of a spring 13. By providing these flanged portions 11 and 12 the spring will remain in the member 1 even though the screws are not in the openings 8 and 9. 80

This spring 13 may be bent in various shapes but as shown in the drawings, by having it first formed in a downwardly extending loop 14 and then an upwardly extending loop 15, a greater resiliency is obtained, than by providing simply one loop. At the lower extremity of the loop 15 the spring curves inwardly as clearly shown in Fig. 5, and is humped around the pin 7, as shown at 16 and finally brought inwardly 90 and the end secured around the flanged portion 12.

Referring now to the supporting portion 2, it will be seen that a base plate 17 is provided in which there are openings for the 95 screws 18 and formed on this base plate and at right angles thereto is the hemispherical portion 19 which has provided on its face a plurality of radial serrations 20. These serrations are simply deep enough for the reception of the spring 13 so that when force is exerted on the mirror the spring will be forced in and out of the said serrations. 100

The pin 7 is fastened in the center of this hemispherical portion 19 and as before mentioned is adapted to slip within the opening in the member 1.

It will be seen that when it is desired to tilt the mirror and have the same remain in its tilted position, the frame is swung with 110 the member 2 thereon and the spring 13 will be forced in and out of the adjacent serra-

tions, and after the frame has reached the desired position, as the spring will be pressed tightly into one of these serrations, it will hold the mirror in this position until the mirror frame is again pushed with the hand.

From the foregoing it will be seen that the stop is one that may be quickly and easily applied, has but few parts and that if for any reason it is desired to remove the spring, 10 it may be easily done, and by looping the said spring as shown a relative great resiliency is obtained.

It is to be understood that many minor changes may be made without departing 15 from the spirit and scope of my invention and although I have shown the same as attached to a mirror, it may be equally as well used on swinging windows, transoms, or other similar articles.

20 Having thus described my invention what I claim as new and desire to secure by Letters Patent is:

1. A stop comprising two members, one of 25 said members provided with a spring and means for holding the spring in said member, the other member provided with a plurality of radial serrations to receive the said spring and said spring having its contacting member positioned parallel with respect to 30 one of the two members.

2. A stop comprising a spring retaining member and a supporting member, a spring in first said mentioned member extending outwardly beyond the side of said member

and adapted to contact with radial depressions in the said supporting member, a pin 35 tle in one of said members and extending into the other member, the contacting portion of the said spring extending in the same vertical plane as that of the said members. 40

3. A stop comprising two members, one of said members having a hemispherical portion formed thereon with radial serrations in its flat face, the other of said members being provided with a spring having a 45 downwardly and upwardly extending loop and adapted to contact with the radial serrations in the other of said members.

4. A stop comprising two members, one of said members having cut out portions on 50 its rear face and a spring located in said cut out portions, means for retaining the ends of the spring in their proper position and said spring being formed at its upper end with a downwardly and upwardly extending loop.

5. A stop comprising in part a member having cut out portions at its rear and sleeves in said cut out portions for the reception of the coiled ends of a spring, said 60 spring being formed with a downwardly and upwardly extending loop and then extending inwardly and then parallel with said member and then inwardly to said sleeve portion. 65

In testimony whereof I affix my signature.

GILLAM D. GODWIN.
